PACKAGING BUFFING COMPOUND AND
LIKE MATERIALSEllsworth T. Candee, Watertown, Conn., assignor
to The Lea Manufacturing Company, a corpo-
ration of Connecticut

Application March 5, 1949, Serial No. 79,901

1 Claims. (Cl. 206—56)

1 This invention relates to the packaging of buffing compounds and like materials. The invention provides a new package of buffing compounds that is particularly economical and convenient to use, and provides a novel container for use in preparing such packages.

Buffing compound and other similar compounds are normally packaged and distributed to the trade in cylindrical containers of paperboard. It is important that the compound be distributed in a closed container, because its composition is critical and must be preserved without substantial change from the time of manufacture until the time of use in order for it to give optimum results. Normally when the compound is to be used the package is opened at the top and the cardboard walls of the container are torn back to expose a portion of the stick of the compound therein. The exposed stick is pressed against the buffing wheel periodically in order to charge it with the compound. As the compound is consumed, the walls of the container are torn back still further, until finally there remains only a nubbin of compound which is no longer of sufficient size to be conveniently held against the wheel. This nubbin is usually discarded. In ordinary cases it amounts to 10 to 20% of the total quantity of buffing compound originally present in the package, and discarding it constitutes a substantial economic waste.

The present invention provides an improved package of greaseless adhesive-containing buffing compound which can be used conveniently without waste, or with very much less waste than heretofore. The new package comprises a paperboard cylinder forming the side walls of a container and having its interior cylindrical surface lined with a layer of substantially non-porous, moisture-impermeable material which is free from the tendency to adhere to buffing compound and which therefore may readily be stripped back from the compound. A substantially rigid metal end closure is secured to one end of the cylinder and reinforces it against collapse; and a false bottom of porous paperboard is mounted in said cylinder in spaced relation with said end closure. The circumference of the false bottom curves downwardly adjacent to the cylindrical wall to form an annular groove with the wall.

The package is completed by a charge of greaseless adhesive-containing buffing compound substantially filling the container above the false bottom and in direct contact therewith. The buffing compound is cast in situ

2 within the cylinder directly against the false bottom and in the annular groove around the circumference of the false bottom, whereby it is fixedly secured to the false bottom. Securing of the compound to the bottom wall is of importance because after the buffing compound has been mostly consumed, the residual nubbin will be torn from the container by the rapidly revolving buffing wheel unless it is firmly anchored in place at the bottom of the container. The side walls of the container below the bottom provide a handhold for supporting the last available portion of the compound against the wheel.

15 The substantially rigid metal end closure provided at the lower end of the container below the false bottom serves to reinforce such end against collapse under a compressive force. It is necessary to grip the package tightly when holding the buffing compound against the wheel, and unless a reinforcing end closure is provided, the handhold at the end of the container is likely to be lost by collapse of the container side walls before all available buffing compound has been consumed. The space between the end closure and the false bottom is substantially free from buffing compound, so that the end of the container where this space exists may be discarded with correspondingly little waste.

30 The improved package of buffing compound and the container therefor in accordance with the invention, together with several alternative arrangements for bonding the buffing compound to the container bottom, are shown in the accompanying drawings, in which

35 Fig. 1 is an elevation of a package in accordance with the invention;

Fig. 2 is a section, on an enlarged scale, taken substantially along the line 2—2 of Fig. 1;

Fig. 3 is a section similar to Fig. 2 but showing a modified form of container bottom; and

Fig. 4 is a section similar to Fig. 2 but showing still another modified form of container bottom.

40 The package shown in Fig. 1 comprises a paperboard cylinder 10 made in the conventional manner by spirally wrapping paperboard strip stock on a cylindrical mandrel and adhesively securing several plies of such stock together. The container is provided with a false bottom 11 formed by a transverse partition 12 located near but spaced from the lower end of the paperboard cylinder. That portion of the cylinder 10 (which forms the side walls of the container) above the transverse partition 12 is filled with buffing compound. The top of the container is closed by a

cover 13, advantageously a metal end closure crimped to the cylinder; and the lower end of the container below the transverse partition is provided with a rigid reinforcing end closure 14, advantageously of metal.

The construction of the container is such that the buffing or like compound with which it is filled does not adhere to the inner surface of the cylinder 10, but is firmly bonded to the false bottom 11. In using the buffing compound, the cover 13 is removed and the paperboard cylinder 10 is stripped back to expose the upper end portion of the compound, which is then pressed against the buffing wheel. As the compound is consumed, the cylinder 10 is stripped farther and farther back. Finally, it is stripped back about to the location of the false bottom, where a peripheral score 15 advantageously is provided to facilitate tearing it off. This score and the false bottom 11 are located about at the position where the residual nubbin of buffing compound would have to be discarded on account of no longer being of sufficient size to provide a handhold for pressing it against the buffing wheel. However, with the improved package, there is very little or no buffing compound in the space below the false bottom 11, and what compound is above the false bottom is firmly bonded thereto so that it may be pressed against the buffing wheel without being torn away. Thereby substantially the entire contents of the package may be safely and conveniently consumed.

The novel features of the package shown in Fig. 1 are more clearly seen in Fig. 2. As here shown, the inner surface of the paperboard cylinder 10 is provided with a lining 16 of aluminum or other metal foil. The lining renders the inner surface of the cylinder non-absorptive, moisture-impermeable, and non-adherent to the charge of buffing compound 17 with which the container is filled. In place of metal foil, some other lining material may be used, such, for example, as a coating of inert plastic material applied in sheet or lacquer form, or even specially treated paper-base materials, such as glassine paper prepared so as to be inert to the buffing compound.

The transverse partition 12 which forms the false bottom of the container is itself advantageously the bottom of an inverted paper cup inserted into the lower end of the cylinder 10. It may be secured in place by means of an adhesive film applied between the outer surface of the cylindrical walls 18 of the cup and the inner surface of the cylinder 10, or by staples 19; or alternatively it may be held in place simply by frictional engagement of the cup walls 18 with the cylinder. The latter alternative provides an especially economical construction, and has been found to be quite satisfactory for most uses of the invention.

The transverse partition 12 is formed of porous paperboard (e. g., pulpboard) or other fibrous and absorptive material which adheres readily to the buffing compound. Further, the periphery 20 of the transverse partition 12 (where it joins with the walls 18 of the inverted cup) is curved at a substantial radius, so that the sides of the cup adjacent the transverse partition are spaced from the interior surface of the cylinder, forming an annular groove 21 about the periphery of the partition 12.

The container above the false bottom 11 is filled with buffing compound in the molten state, and it solidifies in the container. The molten compound penetrates into the annular groove 21, and also penetrates into the pores of the fibrous

material forming the transverse partition 12. Upon solidifying, the bottom end of the charge of compound is firmly bonded to the transverse partition, and is more or less mechanically locked in place by the small quantity that penetrates into the annular groove 21. The degree of bonding (especially that due to adhesion of the compound to the fibrous partition 12) is ample to permit pressing even the last remaining nubbin of compound against a buffing wheel without it becoming torn from the container bottom.

The reinforcing end closure 14 is advantageously of conventional dished metal construction having sides 22 which fit snugly inside the cylindrical walls 18 of the inverted cup, and having its marginal portion 23 turned out and thence crimped in against the outer surface of the cylinder 10. The end closure amply reinforces the end of the cylinder 10 below the transverse partition 12, so that the end portion of the cylinder does not collapse even when tightly gripped for pressing the last of the available buffing compound against the buffing wheel.

The embodiment of the invention described above with reference to Fig. 2 is especially suited for packaging preparations known in the art as "greaseless compounds," which comprise mixtures of glue, water, and abrasive. An alternative embodiment of the invention adapted for use either in connection with greaseless compound or with the mixture of grease and abrasive that is commonly termed "buffing compound" is shown in Fig. 3. In this modification, as in the modification described above, the walls of the container are defined by a cylinder 25 of paperboard, to the inside surface of which is applied a lining 26 of aluminum foil or equivalent moisture-proof, non-absorptive material which does not adhere to the buffing compound. A false bottom 27 for the container is in this case a double structure formed by upper and lower transverse partitions 28 and 29, respectively, which are spaced apart by a short distance and which both are spaced inwardly from the lower end of the container cylinder. The transverse partitions 28 and 29 advantageously are themselves the bottoms of a pair of nested inverted cups having cylindrical side walls 30 and 31, respectively. The side walls of these cups may be secured to each other and to the cylinder 25 by adhesive, or by staples 32, or they may be held in place simply by frictional engagement with each other and with the cylinder. The lower end of the cylinder 25 is reinforced against collapse by a metal end closure 33 similar to the end closure 14 previously described.

The transverse partitions 28 and 29 may or may not be formed of material to which the buffing compound directly adheres, but in any event the upper partition 28 is formed with a series of perforations 34, while the lower partition 29 is imperforate. When the molten buffing compound is introduced into the container, it flows through the perforations in the upper partition into the space between it and the lower partition. When it solidifies, the compound is bonded or anchored to the false bottom 27 by virtue of having that portion of its mass 35 above the upper partition 28 integrally united through the perforations with that portion of its mass 36 between the two partitions.

A package of buffing compound prepared as illustrated in Fig. 3 is used in substantially the same manner as a package prepared as previously described. The cover is removed, and the cylinder is torn back to expose the compound.

An annular score 37 about the periphery of the cylinder 25 may be provided to facilitate tearing off the cylinder about at the location of the upper transverse partition 28. Because the buffering compound is firmly anchored to the double false bottom, it may be consumed safely down to the upper transverse partition 28, after which the lower end of the container (which provides the handhold for applying the last available part of the compound to the buffering wheel) may be discarded. With the modification shown in Fig. 3, discarding of the lower end portion of the container results in the loss of that part 36 of compound filling the space between the two transverse partitions. The amount of compound therein, however, is considerably less than the amount that must be discarded in using buffering compound in the heretofore conventional packages, because the space between the two transverse partitions is small relative to what must be provided for a good handhold for applying the last available portion of the compound to the buffering wheel.

Still another modification in accordance with the invention, which is useful for packaging either greaseless compounds or compounds having a grease base, is shown in Fig. 4. The structure here comprises a paperboard cylinder 40, lined on the inside with a layer of aluminum foil 41 or equivalent, which cylinder defines the side walls of a container for the package. A false bottom 42 for the container is provided in the form of an inverted cup, having side walls 43, inserted into the lower end of the cylinder and held in place either by simple frictional engagement with the cylinder, or by fastening means such as adhesive or staples 44, as in the modifications previously described. The lower end of the cylinder 40 is reinforced by a crimped metal end closure 45.

The bottom of the inverted cup forms a transverse partition 46 spaced an appreciable distance above the lower end of the cylinder 40. This transverse partition is formed with a central opening 47 in which is mounted a shallow cup 48 having distended sides 49. The cup is secured to the transverse partition 46 by having its marginal edge portion 50 crimped against the material of the partition about the periphery of the opening 47.

When molten buffering compound is introduced into the container, it flows into the shallow cup 48, and upon solidification the portion 51 of the compound in the cup is integrally united through the opening 47 with the main body 52 of compound above the partition 46. The distended sides 49 of the cup form undercut surfaces bonding the buffering compound securely to the false bottom 42.

Buffering compound packaged as illustrated in Fig. 4 is used in the same manner as that packaged in accordance with Figs. 1 to 3. After removing the top, the sides of the container are torn back to expose the compound, which is then pressed against the buffering wheel. A peripheral score 53 may be provided to facilitate tearing off the cylinder about at the plane of the transverse partition 46. The buffering compound may be completely consumed down to the partition 46, after the sides have been torn back to the score mark 53, because the compound is securely locked to

the false bottom. The portion of the cylinder below the transverse partition forms a handhold for applying the last available portion of the compound to the buffering wheel. Only that portion of the compound filling the shallow cup 48 is unavailable for use, and the amount thereof is very much less than in the conventional package heretofore used because its volume is much less than is required to provide a good handhold in applying the packaged material to a buffering wheel.

The term "buffering compound" is used extensively in the foregoing specification and in the claim that follows to indicate the composition that is packaged in accordance with the invention. The term is here used in the broad sense to include both the greaseless and the grease-base compounds of commerce for buffering use, and also to include other compounds of a generally similar nature, such as compounds for polishing, deburring and other uses.

I claim:

A package of greaseless adhesive-containing buffering compound comprising a paperboard cylinder forming the side walls of a container, a layer of substantially non-porous moisture-impermeable material lining the interior cylindrical wall surface of said cylinder, said layer being free from the tendency to adhere to the buffering compound, a substantially rigid metal end closure secured to said cylinder at one end thereof and reinforcing it against collapse, a false bottom in the form of an inverted paper cup of porous paperboard mounted in and secured to said cylinder wall with the bottom of the cup forming the false bottom positioned in spaced relation with said end closure, said false bottom forming with said cylinder wall an annular groove, and a greaseless adhesive-containing buffering compound substantially filling the container above the false bottom and in direct contact therewith, said material being cast in situ within the cylinder directly against the false bottom and in said groove, whereby said buffering compound is fixedly secured to the bottom.
